UNITED STATES PATENT OFFICE.

HENRY J. KRACHT, OF GREGORY, SOUTH DAKOTA.

MANURE LOADER.

Application filed March 3, 1921. Serial No. 449,325.

To all whom it may concern:

Be it known that I, HENRY J. KRACHT, a citizen of the United States, residing at Gregory, in the county of Gregory, State of 5 South Dakota, have invented certain new and useful Improvements in Manure Loaders; and I do hereby declare the following to be a full, clear, and exact description of the invention, such as will enable others 10 skilled in the art to which it appertains, to make and use the same.

This invention relates to new and useful improvements in conveyors and particularly to devices for conveying litter from the gutter of a stable to a point exterior of the building.

The principal object of the invention is to provide a device of this character which is constructed and arranged to carry the litter 20 from the gutter, to the outside of the building, and deliver the litter into a manure spreader, or other vehicle.

Another object is to provide a device of this character wherein the liquids and solids 25 are separated from the litter, the solids being carried from the building by the conveyor, while the liquids run from the gutter to a cess pool, or other suitable place or receptacle provided for the purpose.

30 Other objects and advantages will be apparent from the following description when taken in connection with the accompanying drawings.

In the drawings:

35 Figure 1 is a vertical longitudinal sectional view through the gutter, showing the invention in side elevation.

Figure 2 is a top plan view of the same.

40 Figure 3 is a vertical transverse sectional view on the line 3—3 of Figure 2.

Figure 4 is a vertical longitudinal central sectional view on the line 4—4 of Figure 2.

Referring particularly to the accompanying drawings, 10 represents the gutter which runs through a stable, at the open ends of a series of stalls, and in which is caught the litter from the stalls. The floor of the stable is formed from any desired materials, but preferably concrete, and mounted in the gutter, with their ends embedded in the opposite side walls thereof, are the transverse bars 11, each formed from a suitable length of metal pipe. Supported on these bars 11, and extending throughout practically the entire length 55 of the gutter, is a heavy board 12, which is of a width to fit snugly in the gutter. One end of the board is disposed adjacent an opening 13 in the lower portion of the wall 14 of the stable. Carried by the other end of the board 12 are the longitudinally and outwardly extending brackets 15 in which are journaled the ends of a transverse shaft 16, and rotatable with this shaft is a pair of sprocket wheels 17. At the other end of the board 12, inwardly of the opening 13, is a vertical pair of supports 18 in the upper portion of which is supported the shaft 19, and in the intermediate portion the shaft 20. It will be noted that the shafts 19 and 20 extend through and are supported by both 70 of the supports 18. On one end of the upper shaft 19 is mounted a belt wheel 21, which receives power from any suitable motor, while on the other end is mounted a gear 22. Journaled in each support 18, intermediate the shafts 19 and 20, is a short shaft 23 the outer end of each of which carries a large gear 24, while the inner end carries a sprocket wheel 25. Also journaled in the supports 18, between the shaft 20 and the 80 lower ends of the supports, are the short shafts 26. On the outer ends of the shafts 26 are mounted the large gears 27, and on the inner ends the sprocket wheels 28. The ends of the shaft 20 carry the sprocket wheels 85 29 which are disposed between and mesh with the gears 24 and 27 of the shafts 23 and 26. The shaft 20 also has secured thereon a large gear 30 which meshes with the gear 22 of the shaft 19, and by which gear 90 22 the shaft 20 is driven, to impart movement to the sprocket shafts 23 and 26. The end of the board 12, adjacent the opening 13, is supported by a cross bar 31, carried by and extending between the supports 18. Also 95 secured to this cross bar 31, and inclining upwardly and outwardly from the opening 13, externally of the stable, is a board 32, the upper or outer end of which carries the brackets 33 which support the transverse 100 shaft 34, on which are mounted the sprocket wheels 35. Secured within the opening 13, and extending upwardly and outwardly from the wall 14, is a chute 14' having a discharge opening 13' in the outer end of its lower 105 wall.

A pair of endless chains 36 extend from the outer end of the board 12 to the outer end of the board 32, through the chute 14', and engage around the sprockets 17 and the 110 sprockets 35, the upper laps of the chains engage under the sprockets of the shafts 23,

while the lower gaps engage over the sprockets 28. Extending between and connected to the chains 36, are the slats 37, which, when the chain is in motion, scrape the litter along the boards, and carry it out to a point externally of the building, where a wagon, or manure spreader is placed to receive the litter.

From the above it will readily be seen that when the shaft 19 is driven from a motor, motion will be transmitted to the shafts 23 and 26, with the result that the conveyor chains and slats will be set in motion to carry the litter to the waiting wagon, outside of the building.

The liquids from the litter will flow out of the building, by reason of the fact that the gutter is preferably inclined throughout its entire length, said liquids being discharged into a receptacle or suitable place, from whence it may be removed, or otherwise disposed of.

Secured to the outer end portion of the chute 14', and connected to the eye-bolt 38, carried by the wall 14, is a rod or wire 39, for

supporting the chute in proper inclined position, to discharge the litter onto a pile, or into a bin or wagon.

What is claimed is:

A litter carrier for a stable comprising a plurality of transverse bars adapted to be supported in a stable trough, a board supported on the bars, a second board extending upwardly at an angle from one end of the first board, transverse bars supporting the second board, a chute on which the second bars are carried, an endless carrier chain mounted to travel lengthwise of the boards, a sprocket supporting the lower lap of the chain, a driven sprocket engaging on the upper lap of the chain, said sprockets being disposed at the inner ends of the boards, and a drive sprocket operatively engaged with the second-named sprocket.

In testimony whereof I affix my signature, in the presence of two witnesses.

HENRY J. KRACHT.
